UNITED STATES PATENT OFFICE.

AUGUST W. KURZ, OF CLEVELAND, OHIO.

RECEIVING-HEAD FOR CATCH-BASINS.

No. 868,672.

Specification of Letters Patent.

Patented Oct. 22, 1907.

Application filed April 20, 1903. Serial No. 153,364.

To all whom it may concern:

Be it known that I, AUGUST W. KURZ, a citizen of the United States, residing at Cleveland, in the county of Cuyahoga and State of Ohio, have invented certain 5 new and useful Improvements in Receiving-Heads for Catch-Basins, which improvements are fully set forth in the following specification.

This invention relates to improvements in structures of that class employed for capping purposes in connection with catch-basins, the same serving to control, each the entrance to the basin with which it is conjoined, and being commonly known as "receiving-heads for catch-basins."

The object of this invention is to provide a structure 15 of the character indicated which shall be simple and inexpensive as regards construction; durable efficient, and reliable in practical service; which shall be characterized by a marked resistance to service-strains; and which shall possess certain well-defined advantages 20 over prior analogous constructions.

The invention is clearly illustrated in the accompanying drawings, wherein similar reference-numerals denote corresponding parts throughout the several views, and as to said drawings:

25 Figure 1 is a plan view of a receiving-head embodying my said improvements, the man-hole thereof being closed. Fig. 2 is a sectional view designed to more clearly illustrate both the practical application and the details of the general construction, the section, 30 accordingly, being taken centrally and vertically through the head proper, as along the line a—a of Fig. 1, the man-hole cover being removed, and a portion of the basin proper being shown in conjunction with said head. Fig. 3 is a front elevation of said receiving-head, showing the intake and exposed metallic fender thereof. Fig. 4 is a sectional view conforming essentially to Fig. 2, and showing a form of 35 my improved receiving-head modified somewhat as regards certain minor details of the construction. Fig. 40 5 is a detail perspective view illustrating more clearly the essential feature of the modification above referred to, the scale being enlarged.

In a general sense my improved receiving-head comprises an artificial body and a metallic reinforcing member, the materials of said body and reinforcing member, respectively, being at variance in the matter of tenacity, and said reinforcing member being conjoined with said body in a manner to form a fender therefor.

50 It further comprises an artificial body having a man-hole and an intake; a ring or shield within said man-hole; and a metallic reinforcing member, the materials of said body and reinforcing member varying as

above specified, and said reinforcing member being conjoined with said body in a manner to form a fender 55 therefor and also serve as a support for said shield.

In carrying out my invention, reference being had to the accompanying drawings, I make use of a reinforcing member 2, of any appropriate general contour, and formed from metal, as by the process of casting, or directly from metal, as iron or steel, in sheet form. Said reinforcing member is here shown as comprising a horizontal portion or base plate and a portion or plate arranged at an inclination to the horizontal portion, said inclined and horizontal portions being preferably 65 formed integral.

The reinforcing member 2 is provided, at the horizontal portion thereof, with a suitable opening, and thereat there is arranged a vertical shield or ring 3, formed from any suitable material, as metal. 70

The shield aforesaid is here shown as constituting a distinct element of the general construction, and as being removably conjoined with the reinforcing member 2. Said shield may seat directly upon the reinforcing member 2, at the opening aforesaid therein, 75 or the same may be provided with a lateral projection or flange 4, adapted to accordingly seat on said reinforcing member. Further, and where deemed advisable, the ring 3, as a whole, may be formed integral with the reinforcing member 2, as by the process of 80 casting.

A cover 5 is provided for closing the man-hole formed and surrounded by the ring 3, and to receive and support which cover, a cover-seat 6 is arranged within, and adjacent to the upper extremity of, said shield. 85

As will be clearly apparent, the features of construction last under consideration may be otherwise arranged.

For finishing purposes I make use of cement, or other suitable material, 7, primarily in a plastic state 90 and adapted to voluntarily harden, or become hardened, as under the application of heat. The material 7 is disposed, while in a plastic state, so as to form, when hardened, the body of my improved receiving head, and so as to take any desired general contour as 95 a finished product; and as such it is here shown as taking, essentially, an angular general contour, with a somewhat outwardly bowed front surface.

The material 7, while plastic, is placed or arranged upon the reinforcing member 2, around the ring 3, and 100 immediately underneath the inclined portion of said reinforcing member, the latter portion of said material being molded or shaped so as to form an intake 8, for the passage of waste or surface water to and into the basin proper, which may be constructed of masonry 9, 105 as in common practice; and the material disposed at

the upper side of said reinforcing member being brought to a level coinciding with the upper extremity of said shield, by preference.

After being disposed as herein explained, the plastic material is allowed to voluntarily harden; or the hardening thereof may be accelerated by the application of heat.

When constructed substantially as herein described, reference being had to the complete construction, the reinforcing member 2 becomes embedded within the body formed by the material 7; and the inclined portion of said reinforcing member terminates in an exposed edge-segment 2', at the front of the body aforesaid, thus providing for the latter a fender of greater tenacity than said body; and I prefer that the relative arrangement of said reinforcing member with respect to said body be such that the fender thus produced shall occupy a position coinciding with the upper front edge of said body.

20 It is particularly desirable that the body formed by the material 7 be strengthened somewhat above or along the arch of the intake 8, and the construction herein described thoroughly accomplishes this result.

It may be here pointed out that the construction work involved in the production of my improved receiving head, may be performed at the basin in connection with which the head is to be used, or the head as a distinct structure may be produced at a distance from such basin and thereafter transported to such 30 basin and adjusted for service.

For further strengthening the rear portion of the body formed by the material 7, the base 2 may be provided with a vertical spur 3', or a plurality of such spurs.

35 4' denotes an intermediate bed of any appropriate general contour, formed from cement, or other suitable material primarily plastic, as 7, having a reinforcing member 5' embedded therein, and shaped at its upper portion to coöperate with, and form a continuation of, 40 the intake 8. Bed 4' rests on the forward portion of the masonry 9, its upper-surface being flush with the upper surface of the rear portion of said masonry, by preference, and as clearly indicated in Fig. 2. Accordingly, the receiving head proper rests mainly on 45 said masonry and partially, at its front, on the bed 4'.

For the purpose of enhancing the binding effect between the reinforcing member 2 and the material 7, the former may be provided with an opening or with openings 6', indicated in dotted lines in Fig. 1, and 50 more clearly in Figs. 2 and 4, such opening or openings permitting integration of the material 7 therewith. In connection with this binding effect spur or spurs 3' are also of service, as will be readily understood; and the same applies to the angular projection or projections 55 7', illustrated in Fig. 4 as being formed each integral with the member 2, and as modified details of the general construction. Further with reference to the construction shown in Fig. 4, it will be observed that the member 2 is formed in sections bolted or otherwise secured together, and that the reinforcing member 5', for the bed 4', is also provided with the projection or 60 projections 7'.

The operation of my improved receiving head will be apparent from the foregoing description thereof; and

it will be further seen that the same may be modified to some extent without materially departing from the spirit and principle of my invention.

Having fully described my invention what I claim and desire to secure by Letters-Patent, is:

1. In a receiving head for catch basins, a horizontal metallic base-plate, having a manhole opening therein, a vertical manhole ring surrounding said opening, a metallic reinforcing fender-plate upwardly inclined from the base-plate, and an artificial body of concrete, cement, or the like, conjoined with said base-plate and fender-plate and surrounding the manhole ring aforesaid, the said fender plate being exposed at its upper edge beyond the said artificial body, substantially as described.

2. In a receiving head for catch basins, a metallic base-plate having a manhole opening therein, and an upwardly inclined metallic fender-plate made integral therewith, a manhole ring fitting in said opening, and provided with a bearing flange, and an artificial body of concrete, cement, or the like, said body surrounding the said ring, bearing on the base-plate and fender-plate and conjoined therewith, and the upper edge of the said fender plate being exposed beyond the said artificial body, substantially as described.

3. In a receiving head for catch basins, having a manhole opening and an intake opening, a metallic base-plate, a manhole ring surrounding said manhole, an upwardly inclined, reinforcing-plate made integral with said base plate, an artificial body of concrete, cement, or the like, conjoined with said base-plate and inclosing said inclined reinforcing-plate, and means for interlocking the artificial body with said base-plate and reinforcing-plate, the latter projecting above said intake for strengthening said body therewith, substantially as described.

4. A receiving head for catch basins comprising a horizontal metallic base plate having a manhole opening therein, a vertical manhole ring surrounding said opening, a metallic reinforcing fender plate upwardly inclined from the base plate, and an artificial body of concrete, cement, or the like conjoined with said base plate and fender plate and surrounding the manhole ring, an intake opening being formed through said body of concrete below the fender plate, and a reinforcing plate embedded in the concrete below said intake opening.

5. A receiving head comprising a manhole opening and an intake opening, a metallic base plate, a manhole ring surrounding said manhole, an upwardly inclined reinforcing plate connected rigidly with the base plate and extending upward substantially parallel with the upper wall of the intake opening, a body of concrete, cement or the like, surrounding said base plate, manhole ring and reinforcing plate, and a reinforcing plate embedded in the concrete below the lower wall of the intake opening, said plate being substantially parallel with said lower wall, and means for interlocking the artificial body with said base plate and said reinforcing plate.

6. A receiving head for catch basins comprising a base plate formed with a manhole opening therein, an upwardly extending fender plate rigidly connected to the base plate, a reinforcing plate below said fender plate and separated therefrom a suitable distance, and a body of concrete surrounding said base plate, manhole ring, and fender plate, an intake opening being formed through said concrete between the fender plate and the reinforcing plate.

7. A composite receiving head for catch basins comprising a metallic frame and a body of concrete surrounding said frame, an intake opening being formed through the concrete or cement and the manhole opening being formed through the frame.

8. A composite receiving head for catch basins comprising a base plate, a body of concrete formed with an intake opening and a manhole opening, and metallic means supporting the concrete around the manhole opening and intake opening.
